US0D1061388S

(12) United States Design Patent (10) Patent No.: US D1,061,388 S
(45) Date of Patent:  Feb. 11, 2025

(54) MOTORCYCLE FUEL TANK

(71) Applicant: Harley-Davidson Motor Company, Inc., Milwaukee, WI (US)

(72) Inventors: Brad Richards, Galisteo, NM (US); Bjorn Shuster, Hartford, WI (US); Dais Nagao, Menomonee Falls, WI (US); Mike Arndt, Milwaukee, WI (US)

(73) Assignee: Harley-Davidson Motor Company, Inc., Milwaukee, WI (US)

() Term: 15 Years

(21) Appl. No.: 29/879,559

(22) Filed: Jul. 10, 2023

Related U.S. Application Data

(63) Continuation of application No. 29/890,593, filed on Apr. 25, 2023.

(51) LOC (15) Cl. 12-16

CLAIM

The ornamental design for a motorcycle fuel tank as shown and described.

DESCRIPTION

FIG. 1 is a front and left side perspective view of a motorcycle fuel tank showing our new design;

FIG. 2 is a front and right side perspective view thereof;

FIG. 3 is rear and left perspective view thereof;

FIG. 4 is a right side elevation view thereof;

FIG. 5 is a left side elevation view thereof;

FIG. 6 is a front elevation view thereof;

FIG. 7 is a rear elevation view thereof; and,

FIG. 8 is a top plan view thereof.

The broken lines are included for the purpose of showing portions of the motorcycle fuel tank and environment that form no part of the claimed design.

1 Claim, 8 Drawing Sheets
